UNITED STATES PATENT OFFICE.

EDWARD L. ELDRIDGE, OF CAZENOVIA, NEW YORK.

DOOR CHECK AND CLOSER.

No. 813,693.

Specification of Letters Patent.

Patented Feb. 27, 1906.

Application filed October 24, 1904. Serial No. 229,716.

To all whom it may concern:

Be it known that I, EDWARD L. ELDRIDGE, of Cazenovia, in the county of Madison, in the State of New York, have invented new and useful Improvements in Door Checks and Closers, of which the following, taken in connection with the accompanying drawings, is a full, clear, and exact description.

This invention relates to the class of door checks and closers in which a spring-actuated lever is disposed to partially intercept the door in swinging to its closed position and subsequently force the door to complete its movement to said position.

15 The object of the invention is to provide a door check and closer which shall be simple in construction and efficient in its operation without requiring extra devices to be attached to the door; and to that end the invention 20 consists in the improved construction and combination of the component parts of the door check and closer hereinafter described, and illustrated in the annexed drawings, in which—

25 Figure 1 is a front view of my improved door check and closer in position for retaining the door closed. Fig. 2 is a side view of the same. Fig. 3 is a top plan view of the same. Fig. 4 is a plan view showing the 30 door-check in position to intercept the closing door, and Fig. 5 is a plan view showing the door-check moved part way to release the door and to throw the spring-actuated lever into position to force the door to its complete closed position.

Similar letters of reference indicate corresponding parts.

In the said drawings, A represents the door, and B the door-casing.

40 a represents the supporting-plate of the door check and closer, which plate is rigidly attached to the casing B adjacent to the jamb.

b denotes a rigid arm which projects from the face of the plate a and has its free end 45 terminated in a vertical deflection b'.

c and d are two levers formed from one piece of stout wire, which is coiled at f around a spool e, mounted loosely on the end portion 50 b' of the arm b, which constitutes the fulcrum

of said levers. The two levers c and d extend part way in opposite directions from the spool e and thence in directions to allow the free ends of both levers to swing in arcs crossing the arc described by the edge of the door in moving 55 to and from its closed position. Said ends of the levers are preferably provided with rubber or other suitable cushions h for engaging opposite sides of the door. c constitutes the door-closing lever, and d the check-lever, 60 which is shorter than the said closing-lever. The lever c is caused to press the door to its closed position by force of a tractive spiral spring g, which is connected at one end to the supporting-plate a and at the opposite end to 65 a loop i, formed in the lever c.

The two levers c and d and the spring g are disposed in such positions in relation to each other that, at the beginning of opening the door, it pushes the closing-lever c to a position which throws the attaching-loop i of the lever c to the opposite side of the arm b, and then the said spring draws the lever c away from the door, as shown in Fig. 4 of the drawings, and at the same time throws the check- 75 lever d into a position to receive the impact of one side of the door in moving to its closed position, and thus check the said movement of the door. An offset o, formed on the lever c, comes in contact with the side of the arm b, 80 as shown in Fig. 4 of the drawings, and thereby limits the movement of the check-lever d, so as to sustain it in position to check the closing of the door. A subsequent further pressure of the door against the check-lever 85 throws the said lever rearward, as shown in Fig. 5 of the drawings, and finally out of the way and causes the closing-lever c to swing onto the opposite side of the door and force it to its complete closed position, as shown in 90 Figs. 1, 2, and 3 of the drawings.

It will be observed that my described door check and closer is capable of effectually and reliably performing its functions without requiring any extra appliances to be attached 95 to the door, which appliances increase the cost of the door check and closer and are liable to be broken or disarranged or become otherwise inoperative, and thus destroy the utility of the door check and closer.

What I claim as my invention is—

The improved door check and closer consisting of an arm rigidly sustained on the door-casing, a door-checking lever and a door-closing lever rigidly united and fulcrumed on the aforesaid arm, said levers having their free ends adapted to engage respectively opposite sides of the door, and a spring actuat-

ing said levers and throwing the free ends thereof alternately into positions to press on to the door substantially as set forth.

EDWARD L. ELDRIDGE. [L. S.]
